UNITED STATES PATENT OFFICE.

THOMAS J. CHENEY, OF CHICAGO, ILLINOIS, ASSIGNOR OF ONE-HALF TO
WILLIAM R. TUCKER, OF SAME PLACE.

CHURN.

SPECIFICATION forming part of Letters Patent No. 655,391, dated August 7, 1900.

Application filed May 8, 1899. Serial No. 715,910. (No model.)

To all whom it may concern:

Be it known that I, THOMAS J. CHENEY, of Chicago, in the State of Illinois, have invented certain new and useful Improvements in 5 Churns, of which the following is a specification.

This invention relates to that class of churns in which an agitator in the churn-receptacle is connected with operating mechanism placed beneath the receptacle by a shaft extended through its bottom for revolving the agitator. The advantages of this construction are that the operating mechanism can be more compactly disposed of with relation to the receptacle and the operating shaft does not interfere with the use of an ordinary cover on the top of the receptacle. As ordinarily constructed a packing is used where the shaft passes through the bottom to 20 prevent leaking. This increases the friction on the shaft and is otherwise objectionable; and one of the objects of my improvement is to provide means other than a packing in this 25 class of devices for preventing leaking where the shaft passes through the bottom of the receptacle.

The invention also relates to the class of churns in which a combined agitator and aerator is used; and a further object of my improvement is to provide an improved agitator and aerator with a view of effecting proportionally-less agitation by the movement of the agitator and greater aeration and distribution of the air introduced into the liquid 35 by the agitator and in this way to secure equally as good or better results with much less expenditure of power.

I attain these objects by the means illustrated in the accompanying drawings, in 40 which—

Figure 1 is a central vertical section of a churn of the class mentioned provided with my improvements. Fig. 2 is a top view, the cover being removed. Fig. 3 is a detail showing in enlarged side elevation a connecting cap-piece of the tubular shaft of the agitator. Fig. 4 is a detail showing an end view of a detached part.

In the drawings, A is a base-piece provided 50 with radial extensions A', having sockets for legs A² for supporting the base above the

floor. This piece has a vertical extension a at one side, to the upper end of which the drive-wheel B is pivoted and in the lower end of which is journaled a shaft B', connected 55 by a gear b with the drive-wheel. The shaft B' is also journaled in a vertical piece a', depending from the bottom of the base-piece, and provided with a miter-gear b', engaging a gear b² of the operating-shaft C, journaled 60 in a central depending tubular extension a² of the base-piece.

D is the churn-receptacle, rested upon the base or secured thereto by bolts d. The bottom of the receptacle is provided with a central perforation d' for admitting the shaft C, and this perforation is surrounded by the bore of a stationary tube E, secured to the bottom of the receptacle by means of a liquid-tight joint, so as to prevent any escape of liquid 70 from the receptacle into the tube. Said tube is extended from the bottom up to top of the receptacle above the level of any liquid which it is intended to contain. The shaft C is extended through the stationary tube E and 75 provided with a head c or enlargement which will rest upon the top end of the tube and support the shaft in the tube. The upper end c' of the shaft is square. F is a larger rotatable tube, the lower end f of which is fitted to revolve upon the stationary tube E and the upper end of which is connected with the square end c' of the operating-shaft C by means of a cap-piece F', having a square central opening to fit the square end of the operating-shaft and slots f' for engaging pins f² on the rotatable tube, so as to cause said tube to revolve with said shaft. The slots f have lateral or horizontal extensions at the top, whereby the cap can be turned slightly on the 90 rotatable tube, so as to cause the pins to enter the horizontal portion of the slot, and thereby support the weight of the tube suspended on the cap-piece and prevent its dropping down upon the bottom of the receptacle. Near the 95 lower end of rotatable tube F are several openings e, and around each of these is secured to said tube the smaller open end e' of a flattened flaring tube G. The several tubes G radiate from the rotatable tube F, with their 100 larger ends opened, and are placed edge to edge in a plane perpendicular to the axis of

rotation, so that in rotation they follow each other, and the sharp edges cut through the liquid in the receptacle near the bottom with much less friction or resistance than would 5 be the case if broader areas were pushed square against the liquid. Both the interior and the exterior of these flattened tubes are smooth and even from end to end and open at both ends, so as to present as little resistance 10 as possible to the movement of the liquid upon and through them. When submerged and not in action, the liquid fills them and extends up in the rotatable tube F to its level in the receptacle; but when in rotation centrifugal action causes the liquid in the rotatable tube F and the tubes G to be thrown out and displaced by air drawn down through 15 said tube F. The increment of volume outwardly in the radiating outwardly-flaring tubes aids centrifugal action and so produces an increase of downdraft in the rotatable tube F over what non-flaring tubes similarly arranged would produce, and the air thus taken in passes out through horizontally-wide and 20 vertically-narrow exits at the ends of the flattened tubes G and is thereby more widely distributed throughout the liquid at the bottom 25 than heretofore.

This form of agitator and aerator as compared 30 with former forms produces in the liquid less agitation through the agency of the dasher movement and greater agitation through the agency of the introduced air. It, therefore, can be operated with less power 35 than previous devices of this class. Another advantage which it possesses over prior construction is that it can be operated in either direction with equal facility and effect.

The circular motion of the liquid in the receptacle is retarded by narrow perforated 40 plates H, supported against the wall of the receptacle by wire rings h, adapted to fit within the receptacle and hold the plates with one edge against the wall of the receptacle. 45

What I claim is—

1. In a churn of the class mentioned the combination with a receptacle for containing

the liquid provided with a central perforation in the bottom, of a stationary tube secured with one end over the perforation by a liquid-tight connection with the bottom and extended up in the receptacle above the space for containing the liquid, the operating-shaft extended through the bore and projecting above the open end of the stationary tube and provided with means for supporting it vertically therein, a rotatable tube mounted on the stationary tube and connected with the projecting upper end of the operating-shaft so as to rotate therewith, an agitator mounted on the revoluble tube, and operating mechanisms connected with the operating-shaft below the bottom of the receptacle as specified. 65

2. In a churn of the class mentioned the combination with a receptacle for containing the liquid provided with a central perforation in the bottom of a stationary tube secured with one end over the perforation by a liquid-tight connection with the bottom and extended up in the receptacle above the space for containing the liquid, the operating-shaft extended through the base and projecting above the open end of the stationary tube and provided with means for supporting it vertically therein, a tube rotatably mounted on the stationary tube with intervening air-space and rigidly connected with the projecting upper end of the operating-shafts so as to rotate therewith, a series of open-ended flaring tubes radially mounted upon the rotatable tube near the bottom in a plane perpendicular to the axis of rotation, the small ends of said flaring tubes being connected so as to communicate with the bore of the rotatable tube and the larger ends being flattened so as to straighten the upper and lower sides of said flaring tubes and form an acute ovate opening and exterior 75 therefor, and mechanism for operating said rotatable tube as specified. 80
